UNITED STATES PATENT OFFICE.

LOUIS J. JOHNSON, OF MISHAWAKA, INDIANA, ASSIGNOR TO JOHNSON BROS. ENGINEERING CORPORATION, OF SOUTH BEND, INDIANA.

TILLER FOR OUTBOARD MOTORS.

Application filed February 13, 1922. Serial No. 536,319.

To all whom it may concern:

Be it known that I, LOUIS J. JOHNSON, a citizen of the United States, residing at Mishawaka, in the county of St. Joseph and State of Indiana, have invented certain new and useful Improvements in Tillers for Outboard Motors, of which the following is a specification.

The invention relates to tillers for outboard motors of the type used on small craft, and particularly to the type wherein the motor is pivotally mounted and movable in a horizontal plane, and pivoted for tilting in a vertical plane. Heretofore tillers for motors of this character have been rigid and when the motor is tilted in a vertical plane, such for instance as when the boat on which the outboard motor is mounted enters shoal water, which causes a pivotal movement of the motor in a vertical plane, the tillers become broken or limit the pivotal movement of the motor by engagement with a portion of the boat, usually the rear seat. To overcome the above difficulty it is the object of the invention to provide the motor with a substantially horizontally disposed tiller, which tiller is hingedly connected to the motor in such a manner that it may move upwardly when it comes into engagement with an obstruction and will be limited in its downward movement. Also to provide means whereby the tiller may be moved to a position where it will fold downwardly to a position adjacent the motor.

With the above and other objects in view the invention resides in the combination and arrangement of parts as hereinafter set forth, shown in the drawings, described and claimed, it being understood that changes in the precise embodiment of the invention may be made within the scope of what is claimed without departing from the spirit of the invention.

In the drawings:—

Figure 1 is a top plan view of the outboard motor, showing the tiller applied thereto.

Figure 2 is a sectional view through the stern of a conventional form of boat, showing the motor applied thereto, and the tiller.

Figure 3 is a transverse sectional view through one side of the tiller yoke.

Figure 4 is a top plan view of the inner end of the tiller, showing clamping cleat re-

Referring to the drawing, the numeral 1 designates the engine of the outboard motor and 2 a downwardly extending shaft casing carried thereby, which shaft casing is pivotally mounted in the bearing member 3 in such a manner that the motor may be rotated in a horizontal plane. The bearing member 3 is pivotally connected at 4 to the clamp 5 secured to the stern 6 of the boat 7, thereby allowing the outboard motor as a whole to be tilted in a vertical plane, for instance when going over shoal water, so that the propeller driven by the motor, which propeller is not shown, will clear the bottom of the stream. The casing 2 is provided with segmentally shaped flanges 8, which flanges engage over flanges 9 carried by a block 10 in the slotted segment 11, that is when the motor is rotated for reversing the direction of movement of the boat 7. It will be seen that the outboard motor may swing in a horizontal plane during the steering operation of the boat, and may be tilted in a vertical plane on the pivotal point 4 as desired. It has been found that when boats having motors of this character run into shoal water, the motor is tilted by engagement with the bottom of the stream, and that rigidly fixed tillers carried thereby come into engagement with parts of the boat, usually the rear seat 12, thereby causing the tiller to bend or break, or the shafting or casing 2 to be bent or damaged.

Extending forwardly from the forward side 13 of the motor 1 is a horizontally disposed U-shaped yoke 14, on the transverse portion 15 of which the tiller 16 is pivotally mounted, and is also slidably mounted, but frictionally held on said portion 15, thereby allowing the tiller to swing upwardly in the direction of the arrow *a*, and at the same time, under pressure, to be moved transversely on the portion 15 of the yoke 14. The tiller 16 comprises a right angled shaped member 17, the arm 18 of which is provided with a semi-circular recess 19 for the reception of the underside of the transverse portion 15 of the yoke and with a rearwardly extending arm 20 having a semi-circular recess 21 for the reception of one of the side arms 22 of the yoke 14. The arm 20 forms means for limiting the downward movement of the tiller 16 and also forms means when in engagement with the arm 22, whereby the outboard motor as a whole may

be tilted in a vertical plane, for instance when the boat is going through shoal water and is being moved for steering purposes. If the motor is suddenly tilted by engagement of the lower end thereof with the bottom of a stream, the tiller 16 when it comes into engagement with the seat 12 or any other obstruction will be forced upwardly, thereby allowing a full movement of the motor in vertical plane without being limited by the engagement of the tiller with the seat, as clearly shown in dotted lines in Figure 2. The tiller is frictionally held on the transverse portion 15 of the yoke 14 by means of the plate 23, which arches the upper side of the portion 15 and is secured by means of screws 24 to the arm 18 of the member 17. It will be seen that by adjusting the screws 24 that the frictional engagement of the tiller with the portion 15 of the yoke 14 may be varied. By slidably mounting the tiller on the portion 15 of the yoke, it will be seen that by tilting the tiller 16 upwardly until its arm 20 is out of engagement with the arm 22 of the yoke 14, that the tiller can be moved inwardly, for instance to the dotted line position, shown in Figure 1, at which time the tiller may be tilted downwardly to a position where it will be close to the casing 2 of the motor, in which position it will allow the motor to be packed compactly and the motor easily moved from place to place, for instance on the running board of an automobile, as is now the practice.

The invention having been set forth what is claimed as new and useful is:—

1. The combination with an outboard motor movable in a vertical plane and in a horizontal plane, of a tiller for controlling said motor in its movement, said tiller being pivotally connected to the motor and movable upwardly in a vertical plane, limiting means for limiting the downward move-

ment of the tiller in a vertical plane and means whereby said tiller may be moved transversely and swung upwardly and downwardly in a vertical plane.

2. The combination with an outboard motor movable in a vertical and a horizontal plane, of a tiller for controlling said motor in its movement, said tiller being pivotally connected to the motor and movable upwardly in a vertical plane, limiting means for limiting the downward movement of the tiller, and means whereby said tiller may be moved transversely and swung downwardly to a position adjacent the motor.

3. The combination with an outboard motor movable in a vertical and a horizontal plane, of a tiller for controlling the motor in its movement, said tiller comprising a right angled member, the arms of which have recesses, a U-shaped yoke carried by the motor, the transverse portion of the yoke being disposed in a recess of one of the arms, the arm of the yoke being disposed in a recess of the other arm of the tiller, a member arching the transverse portion of the yoke, and having adjustable connections with one of the arms of the tiller thereby forming a pivotal and a slidable connection between the tiller and the yoke, and a handle member extending outwardly from the tiller arms.

4. The combination with an outboard motor supported on a boat, said motor being pivotally mounted and movable a substantial distance in a vertical plane, said motor being movable in a horizontal plane, of a tiller for said motor, said tiller comprising a transversely disposed bar carried by the motor and a pivoted tiller handle slidably mounted on the transversely disposed bar and movable in a vertical plane independent of the movement of the motor.

In testimony whereof I affix my signature.

LOUIS J. JOHNSON.
